F. E. PFEIFFER

AUTOGRAPHIC REGISTER

Filed June 30, 1924

UNITED STATES PATENT OFFICE.

FRANK E. PFEIFFER, OF DAYTON, OHIO, ASSIGNOR TO THE EGRY REGISTER COMPANY, OF DAYTON, OHIO, A CORPORATION OF OHIO.

AUTOGRAPHIC REGISTER.

Application filed June 30, 1924. Serial No. 723,194.

My invention relates to autographic registers.

It is the object of my invention to provide an autographic register which will 5 eliminate the usual outside stop to limit the movement of the handle to one revolution.

It is also an object of my invention to provide means for ejecting strips of different lengths with the same mechanism, 10 save for the changing of a single part which does not disturb the rest of the mechanism, thus providing substantially a single model for use with all lengths of tickets which need only be changed in one part to adapt 15 it for each length of ticket, thus effecting great economies in production.

It is a further object of my invention to provide a stop which necessitates the operator removing his hand from the 20 machine to operate it, thus preventing the movement of the handle beyond the stop without first bringing the handle to rest.

In this machine embodying my invention it is also possible to mount the operating 25 handle directly on the main shaft which carries the paper ejecting means thus effecting economies of construction as elaborate gearing is rendered unnecessary such as has been the case when the driving handle has 30 been remotely located from the paper ejecting means.

Referring to the drawings:

Figure 1 is a side elevation of a complete 35 register embodying my invention.

Figure 2 is a section on the line 2—2 of Figure 3.

Figure 3 is a plan view of one corner of the register adjacent the operating handle with a cover plate and writing table broken 40 away to show one side of the paper actuating mechanism, the gearing and stop.

Referring to the drawings in detail:

1 is a base plate, 2 is a side plate mounted thereon of which there are a pair forming 45 the side walls of the register which is provided with the conventional front and end plates not shown. The register contains a plurality of rolls of paper 3 which are led upwardly and over the usual writing table, 50 under the writing cover 4 which is held down through the agency of the hooks 5 and 6 at the front of the machine.

The paper is actuated by any desirable means, which in the present instance con-

sists of pin wheels 7 on either side of the 55 machine within it mounted upon the main shaft 8. The pins 9 on the pin wheel engage with the conventional marginal perforations in the paper which is commonly used in this art.

Mounted upon this main operating shaft 8 is a gear 10 on the inside of the register and an operating handle 11 on the outside of the register. This gear 10 meshes with an intermediate gear 12 which in turn 65 meshes with a form length gear 13. The gear 12 is mounted upon a stud shaft 14 carried by a plate 2^a pivoted about the shaft 8 and adjustably secured by a pin 30 to the wall of the register through the medium of 70 a slot 31 so that the gear 12 may be positioned to mesh with different sized gears 13 for the purpose presently to be stated. The driving gear 13 is mounted on the stud shaft 15 in the wall of the register. On this shaft 75 is carried a collar 16 which may be a part of the gear itself or be adapted to turn with the gear. On this collar 16 is a projecting stud 17. Engaging with this stud when it makes a single revolution is the finger 18 which is pivoted on the bracket 19 as at 20. This finger has an outside finger piece 21 so that it can be moved out of engagement with the stud 17. This finger is held in 80 engaging position by the helical spring 22 which is connected with the finger at 23 and to the register at 24.

A pawl 25 is pivotally mounted on the register wall so that its tooth 26 will engage 85 with the teeth of the gear 13 to prevent the backward movement of the mechanism.

It will be apparent that by changing the gear 13, the distance to which the paper will be ejected at each stroke of the handle will 90 be also changed. The handle does not make a complete revolution and come to rest at the same point as has heretofore been the practice but the handle in this instance will revolve one or more revolutions or fractions thereof prior to coming to rest, depending upon the length of form to be ejected which in turn depends upon the size of the gearing. It is thus possible by having one gear interchange with another to produce the same machine with that exception for all lengths of forms, thus greatly reducing the complexity 95 of models and the number of models which must be kept in stock effecting a considerable 100 105

economy in the investment in stocks of registers.

From the foregoing description, the operation of the device will be readily understood. When the machine has been properly loaded and supplied with a gear 13 of the size adapted to release the desired length sheet, the operator turns the handle 11 until the gear 13 has made one complete revolution 10 when the stop 17 will come in contact with the finger 18 and prevent further rotation of said handle. This insures a complete stopping of the mechanism before another sheet or form may be ejected. The operator then 15 moves the finger 18 by the part 21, extending on the outside of the register, when the gear 13 will be free to move upon further turning of the handle. Should it be desirable to 20 change the length of the sheet that is being fed out of the machine upon each operation, a gear of different size may be substituted for the gear 13 and the gear 12 adjusted to

cooperate therewith by moving the plate 2^a on which it is mounted, as heretofore described.

25

It will be understood that I desire to comprehend within my invention such modifications as may be necessary to adapt it to varying conditions.

Having thus fully described my invention, 30 what I claim as new and desire to secure by Letters Patent is:

In an autographic register having a plurality of sheets to be fed therefrom, an actuating handle adapted to be rotated in one direction, a gear operated by said handle to determine the length of the sheet to be fed, a collar rotated with said gear, a stud carried by said collar, a laterally movable finger to engage said stud on one revolution of said 35 gear, and a spring to hold said finger in engaging position.

In testimony whereof, I affix my signature.

FRANK E. PFEIFFER.
